UNITED STATES PATENT OFFICE.

ALEXANDER B. McLAUGHLIN, OF CHICAGO, ILLINOIS, ASSIGNOR OF ONE-THIRD TO WALTER E. SUMMERS, OF SAME PLACE.

DEVICE FOR SUPPORTING AND LOWERING CENTERS FOR TILE-ARCHES.

SPECIFICATION forming part of Letters Patent No. 532,005, dated January 1, 1895.

Application filed October 8, 1894. Serial No. 525,815. (No model.)

To all whom it may concern:

Be it known that I, ALEXANDER B. McLAUGHLIN, a citizen of the United States, residing at Chicago, county of Cook, State of Illinois, have invented a certain new and useful Improvement in a Device for Supporting and Lowering Centers for Tile-Arches; and I declare the following to be a full, clear, and exact description of the invention, such as will enable others skilled in the art to which it appertains to make and use the same, reference being had to the accompanying drawings, which form a part of this specification.

My invention is designed to provide improved means for supporting and lowering centers for tile arches and has for its object improved devices for this purpose whereby the tiles in an arch may be filled in completely and for doing away with the necessity of keying up the arch after the center has been lowered.

Another object of my invention is to do away with the obstructions heretofore common in the way of laying the tile, my invention enabling the workmen to do better and quicker work and to do their work more conveniently.

To these ends my invention consists of the construction, combination, and arrangement of devices and appliances hereinafter described and claimed, and illustrated in the accompanying drawings in connection therewith, in which—

Figure 1 is a partial vertical section, showing parts in elevation, of portions of a building. Fig. 2 is a detail sectional view illustrating the old method and means of laying tile arches, heretofore used. Fig. 3 is a detail view of a portion of an arch at right angles to the section shown in Fig. 1. Fig. 4 is a plan view of Fig. 1. Fig. 5 denotes a suitable lever employed in detaching certain portions of the device as hereinafter explained.

In Figs. 1 and 4 I have illustrated my device in connection with two adjacent stories or floors of a building.

A denotes the customary horizontal steel I-beams commonly employed in buildings where tile floors or arches are employed.

50 A' denotes the vertical beams.

B denotes individual tiles of which the arch is constructed.

C denotes what is termed a "center" upon which the tiles are supported while the arch is being laid and keyed up. These centers 55 are constructed in the ordinary manner, and consist usually of wooden "ledgers" D, shown in dotted lines, Fig. 4, with their ends projecting. These ledgers are commonly formed of two pieces of timber d, d', spaced apart, forming a passage way, shown at d² therebetween. Upon these ledgers planks D' are laid for supporting the tile while being laid thereupon.

To more fully understand my improved devices for supporting tile centers while the arch is being laid, and for lowering the centers after the arch has been completed, I have shown in Fig. 2 the old devices and method heretofore commonly employed, consisting 60 of a ledger E laid at right angles to the ledger D and adjacent to the arch to be laid.

In Fig. 2 the center C is shown supported adjacent to the base of the I-beams A, while the ledger E is supported upon the top of the 75 same I-beams, customarily with a block of brick or other suitable material shown in Fig. 2 at F. To work the tiles adjacent to the ledger E, it is necessary to elevate them a suitable distance above the adjacent I-beams 80 A, requiring one or more bricks or blocks F upon said I-beams underneath the ledger E.

The centers C have heretofore commonly been supported by means of rods G provided at their lower ends with hooked or flanged 85 plates G' engaged underneath the ledger D, the bolt G passing upward through the channel d² between adjacent planks and through the ledger E, a nut G² serving to tighten the rod G in place, a washer g usually intervening 90 between the ledger E and the nut G². It will be observed that the ledger E is located adjacent to the arch to be laid and near its upper surface. The ledgers E so located adjacent to the arch are very much in the way of the 95 workmen in seriously impeding their work and rendering it laborious and slow to place the tile in position adjacent thereto. The ledgers E being located adjacent to the arch to be laid have thus been heretofore a con- 100

stant obstruction in the way of the workmen. To lower this center, as heretofore commonly supported and arranged, it has been customary to lower a rope through the channel d^2 in the ledger E, the ledger E being constructed analogous to the ledgers D, having a hook thereto attached, the hook passing through the channel d^2 of the ledger D and engaging underneath the ledger D. The nut G has then 10 been removed while the workmen support the centers by means of ropes so engaged with the ledgers D, after which the workmen at the ropes lower the center of the floor below. By the old method, however, it was impossible to 15 wholly complete the arch before the center was lowered away, inasmuch as it has been necessary to leave out a key from the arch adjacent to the bolts G, commonly four in number, to support an individual tile center. 20 After the center has been lowered away, the workmen must then return to the arch to insert the omitted key tiles from the arch. The omission of the keys until the centers were lowered away, necessarily left the adjacent 25 tile in a position liable to displacement, as they were liable to be easily slipped out of position and to fall through if stepped upon, in which case it became necessary to raise a tile center underneath to put the displaced tile 30 back into position. This liability of portions of the tile adjacent to the omitted key being slipped out of place and the consequent necessity of their replacement, together with the obstructions in the way of the workmen, heretofore common, have rendered it very desirable 35 that these differences should be overcome, and I will now proceed to describe how my improved appliances very effectually overcome these differences and hinderances where- 40 by the former obstructions may be done away with in laying the tile and whereby the keying up of the arch after the center has been lowered away, is no longer required.

I carry out my invention as follows: The 45 center C is constructed in the usual manner. Instead, however, of locating the supporting ledgers adjacent to the top of the I-beams between which the tile are to be laid, I carry supporting ledgers, which I have indicated at 50 D², to the floor or story above that on which the arch is to be laid, as indicated in Figs. 1 and 4. Instead of rods G heretofore commonly used, engaged with the ledgers D, I employ a rod H provided with a flanged plate or base H' engaging the lower edges of the ledger D, the rod H being, say, an inch and a quarter in diameter, or of suitable dimensions, a nut h on its lower end holding the plate H' in position. The rod H, toward its upper end 55 and above the completed arch, is cut away, as shown at h', to form a shoulder thereabove, as shown at h². To form this shoulder, the rod H may simply be recessed annularly a slight distance. Above the shoulder h² the 60 rod H is threaded, as shown at h³. Upon the upper end of the rod H, I engage any suitable connecting device having a screw threaded

connection therewith. The rod H at the left hand in Fig. 1 is shown engaged at its upper end by a head-piece J having an eye, as at j, 70 at its upper end. K denotes an additional rod threaded at its upper end and engaged with the ledger D² located at the story above the arch to be laid, the rod K being provided at its upper end with a nut k. A chain L is 75 shown at the left hand in Fig. 1 connecting the rod K with the head-piece J, the lower end of the chain being formed with a hook engaged in the eye j. At the right hand in Fig. 1, instead of connecting the rods H and K by means of a chain L and a head-piece J, I have shown a turn-buckle M engaged at its extremities with the adjacent extremities of the rods H and K.

N denotes a lever of suitable construction 85 to engage the shouldered portion of the bars H. As shown, the lever N is constructed with a fork n at one end to engage the rod H at the recessed portion h' thereof, the fork n engaging under the shoulder h². In laying 90 the arch, the tiles B are laid directly up against the rod H, the keys all being laid in place, it being unnecessary to omit any tile or keys in order to lower away the center. When the arch has been wholly completed and the workmen are ready to lower away the center, the implements N are engaged with the shoulders 95 h² of the rods H by means of which the centers may be supported while the devices connecting the bars H and K are separated from 100 the bars H or detached therefrom.

When a chain, as shown at the left hand in Fig. 1 at L, is employed as a connecting device, its lower end may be unhooked from the eye of the head-piece J, the bar H being 105 supported in position by means of the implement N. With the head-piece J is engaged a rope or cable P by means of which the workmen may lower the center. It will be observed that the head-piece J is of the same 110 diameter as that of the body of bar H so as to pass through the orifice in the arch occupied by the bar. It will be understood that ordinarily four bars H are employed to support a center, as shown in Fig. 4, although they 115 may be of any required number. In this case, the four bars H are supported by means of the levers N as hereinbefore described, while the bars K are detached therefrom, after which by means of the ropes or cables P attached to the head-pieces J the centers are 120 lowered away.

In case turn-buckles or analogous devices are employed to connect the bars H and K, when the bar H has been disconnected therefrom, a rope with a head-piece J attached thereto is secured upon the upper end of the rod H whereby the center may be lowered away as above described. It will thus be perceived that the arch is fully completed, no 125 keys or tiles being omitted before the center is lowered away. The orifice occupied by the bar H may be filled in by the plasterer. There 130 is thus no liability whatsoever of the displace-

ment of any of the keys or tiles of the arch after the center has been lowered away. At the same time the supporting cross pieces or ledgers D² being located on the I-beams at 5 the story or floor above that on which the arch is to be laid carries said supporting ledgers or cross pieces up above and entirely out of the way of the workmen so that they are unimpeded and unobstructed thereby in their 10 work, in consequence of which they are enabled to work much more rapidly and more efficiently, thereby enabling them to do a better job and in much less time than has heretofore been possible. There is in this way no 15 keying up of said arch to be done after the center is lowered away therefrom.

Instead of employing a nut h on the lower end of the rod H, said rod may be rivet-headed.

Where a turn-buckle M is employed, it will 20 be convenient to coil the rope once or twice therethrough to facilitate the lowering of the center, as the center is usually too heavy to be lowered by a straight hold upon the rope. In place of making the shoulder h² integral 25 with the rod H, a nut might be run down upon the rod to answer the same purpose.

It will be understood, as hereinbefore explained, that in the old method it has been necessary to leave out certain portions of the 30 tile in order to provide room for lowering the old fashioned hook through the arch and between the members d, d' of the ledger D. Moreover, when such a space has been left by the omission of a tile the space is liable to 35 come over one of the separating blocks, shown at Q, Fig. 4, in which case it has been necessary to take out more of the tile to give opportunity to lower down the old fashioned hook between the members d and d' to engage 40 the ledger D.

What I claim as my invention is—

1. In a device for supporting and lowering centers for laying tile arches, the combination of the ledgers D, the ledgers D², rods H 45 engaged with the ledgers D, the rods K engaged with the ledgers D² and having removable connections with the rods H respectively, substantially as set forth.

2. In a device for supporting and lowering 50 centers for laying tile arches, the combination of the ledgers D, the ledgers D², rods H engaged with the ledgers D, the rods K engaged with the ledgers D² and having removable connections with the rods H respectively, 55 and means to support the rods H in disconnecting the rods K therefrom, substantially as set forth.

3. In a device for supporting and lowering 60 centers for laying tile arches, the combination of ledgers D to support the arch, the rods H engaged therewith at their lower ends and extending through the completed arch, and means to engage the upper ends of said rods to lower the center, said rods each constructed with a shoulder h² and cut away

therebeneath, substantially as and for the purpose set forth.

4. In a device for supporting and lowering centers for laying tile arches, the combination of the ledgers D, the ledgers D², the rods H each constructed with a shoulder toward its upper end and engaged with the corresponding ledger D at its lower end, the rod K engaged with the ledgers D² and having removable connections with the rods H respectively, 70 and means to engage said shoulder on the rods H to support said rods in disconnecting the rods K therefrom, substantially as set forth. 75

5. In a device for supporting and lowering 80 centers for laying tile arches, the combination of the ledgers D, ledgers D², the rods H engaged with the ledgers D, the rods K engaged with the ledgers D² and each having a removable connection with the corresponding 85 rod H, and a lever engageable with each of the rods H to support the same in disconnecting the rods K therefrom, substantially as set forth.

6. In a device for supporting and lowering 90 centers for laying tile arches, the combination of the ledgers D, the rods H engaged therewith, the ledgers D², the rods K engaged therewith, a connection between the rods K and H having a removable engagement with 95 the rod H, a head-piece engageable with the rod H, a rope or cable engaged with said head-piece, and means to support the rod H in disengaging said connection therefrom, substantially as set forth. 100

7. In a device for supporting and lowering centers for laying tile arches, the combination of the ledgers D located below the I-beams of the floor upon which the tile arch is to be laid and supporting a center thereupon, rods 105 H engaged with said ledgers, ledgers D² located upon the I-beams of the floor above that on which the arch is to be laid, rods K engaged with the ledgers D² and removably connected at their opposite ends with the rods H, and 110 means to support the rods H in disconnecting the rods K therefrom, and for lowering the rods H with the center supported thereby, substantially as set forth.

8. In a device for supporting and lowering 115 centers for laying tile arches, the combination of the ledgers D, the rods H engaging said ledgers and extending through the completed arch, a perforated head-piece J of a diameter not greater than the diameter of the 120 rod, engaged with the upper end of said rod, and a rope or cable connected with said head-piece, substantially as and for the purpose set forth.

In testimony whereof I sign this specification in the presence of two witnesses.

ALEXANDER B. McLAUGHLIN.
